UNITED STATES PATENT OFFICE.

DANIEL O. SNOOK, OF KANSAS CITY, KANSAS.

SANDER NOZZLE.

Application filed February 16, 1924. Serial No. 693,229.

To all whom it may concern:

Be it known that I, DANIEL O. SNOOK, a citizen of the United States, residing at 653 Kansas Ave., Kansas City, in the county of Wyandotte and State of Kansas, have invented a new and useful Sander Nozzle, of which the following is a specification.

The present invention relates to track sanding devices, and aims to provide a novel and improved device of this character in which the proper flow of the sand is facilitated, the invention having particular reference to sander nozzles in which the flow of the sand is induced by a compressed air connection.

A further feature of the invention is the provision of a compressed air connection including a nozzle device the construction of which is adapted to prevent any clogging of the air passage with any foreign particles, and in which means are provided for the trapping of any such waste or foreign matter within a chamber from which such matter may be removed from time to time.

It is also sought to provide a construction adapted for connection to the sand feeding conduit by either a direct horizontal arrangement, or in such a relation as requires an angular assembly of the parts comprising the nozzle attachment.

With this general object in view, the invention will now be described with reference to the accompanying drawing illustrating two different forms of embodiment of the improvement, after which those features deemed to be novel will be particularly set forth and claimed.

In the drawing—

Figure 1 is a longitudinal sectional view of a sander nozzle constructed in accordance with the present invention;

Figure 2 is an elevation, on a reduced scale, showing the device attached to a sand feeding conduit, with a part of the sand supply box included in the view; and

Figure 3 is a sectional view, partly in side elevation illustrating a modified form of arrangement of the device in relation to the sand feeding pipe.

Referring now to the drawing in detail, and more particularly to Figures 1 and 2, this illustrates the improved device in its operative relation to a sand feeding pipe 4 leading from a sand box 5, and connecting with a sand delivery pipe 6 through the medium of a four-way cross or union joint 7

fitted with the usual clean out plug 8. At a point opposite to the connection of the union 7 with the pipe 6, there is threaded into said union 7 the discharge end of the nozzle member 9 forming a part of my improved device, and designed for conducting air into the path of flow of sand through the sand conduit, as illustrated in Figure 1. The discharge end of the member 9 projects sufficiently within the interior chamber 10 of the union 7, for the purpose of intersecting the path of sand flow, and this extremity of the member 9 is suitably cut away and rounded off, as indicated at 11, for the purpose of avoiding any tendency of this part of said member to obstruct the flow of sand or clog up the passage 10, as might occur if angular or flat surfaces were presented to the flow of sand at this point.

In the construction illustrated in Figures 1 and 2, the nozzle member 9 is bent at right angles, as indicated at 12, and the receiving end of this member 9 is fitted with a tubular element 14, suitably threaded, as indicated at 15, for attachment to the receiving end of said member 9. To this end of the member 9 is also clamped a casing element 16 having an interior flange 17 fitting the element 14, and formed with a ground surface for tight fitting relation with the member 9 around the margin of said element 14, in which relation the parts are clamped by a collar 18 engaging an exterior flange 19 on the casing 16 and having an interior thread for attachment to the outer margin of the receiving end of said member 9. The hollow interior of the casing 16 is of greater diameter than the element 14, as clearly illustrated in Figure 1, thus forming a trap chamber 20 for the collection of any waste or foreign particles which may be caught within this chamber as the air flows thereto from a suitable compressed air connection 21 and thence through the air passages 22 and 23 in the element 14 and nozzle member 9, respectively.

One of the novel features of the improved construction, in this connection, is the tapering of the air passage 22, throughout its length, beginning with the receiving end of said passage in the chamber 20 and gradually increasing in diameter toward the other end of said passage which communicates with the passage 23 through the nozzle member; and, preferably, this latter passage 23 is also of a gradually increasing diameter

from its point of communication with the passage 22, to the discharge end of said passage within the chamber 10 where it meets with the flow of sand through the union or 5 joint 7.

Where the connection of the air line 21 is to be made to the sand feeding conduit by a straight horizontal connection, without any bend in the air line at the nozzle, 10 I employ the construction illustrated in Figure 3. In this arrangement, the angular nozzle member 9 is not required, but simply a straight sleeve member 25, mounted by means of a bushing 26 in one of the openings of the union 7, the discharge end of said sleeve 25 being rounded or tapered off, as illustrated at 25'. This sleeve 25 is connected to the casing 16 by means of a joint element 27 similar to the receiving end of 15 the nozzle member 9, and provided with a socket portion 28 for receiving one end of the sleeve 25. The element 27 is secured to the casing 16 through the medium of the collar 18, in the same manner as the nozzle member 9, as illustrated in Figure 1.

It will thus be seen that I have provided a simple and practical device for carrying out the objects of the invention. On account of the gradually increasing size of 30 the air passage 22, in the direction of flow of the air therethrough, there is no opportunity afforded for the packing of any foreign particles in said passage, since the increasing size of the passage simply permits the loosening up of such matter, and entire freedom of movement through the passage into the sand chamber 10. When the flow of air enters the trap chamber 20, which is in communication with the point 35 of smallest diameter of the air passage 22 through the nozzle, the usual action at this point will be the prevention of any waste or foreign particles from entering into the passage 22, thus trapping such foreign matter in the chamber 20, from which it may be removed from time to time, by simply loosening the collar 18, when the tubular element 14 may be removed for cleaning both it and the interior of the casing 16.

50 Another important advantage of the improved construction is the provision of the

tapered or rounded contour at the discharge end of the nozzle member 9, or the sleeve member 25, which as above explained prevents any clogging in the chamber 10 by 55 presenting no surface to the flow of sand which would have any tendency to obstruct the free flow thereof.

While I have illustrated what I now regard as the preferred form of construction 60 for embodying the proposed improvements, I desire to reserve the right to make such changes as may fairly fall within the scope of the appended claims.

What I claim is:—

65 1. A sander nozzle comprising, in combination with the sand feeding pipe, an attachment formed with an air passage arranged to discharge into said pipe, the major portion of said air passage being of gradually increasing diameter in the direction of the discharge end of said passage.

70 2. A sander nozzle comprising, in combination with the sand feeding pipe, an attachment formed with an air passage arranged to discharge into said pipe, a portion of said air passage being of gradually increasing diameter throughout its length in the direction of the discharge end of said passage, said attachment having a trap 75 chamber for waste at the small end of said passage.

80 3. A sander nozzle comprising, in combination with the sand feeding pipe, an attachment formed with an air passage of 85 gradually increasing diameter throughout its length and communicating with said sand pipe at the point of greatest diameter of said passage.

85 4. A sander nozzle comprising a casing 90 adapted for attachment to the compressed air line, a nozzle element attached to the discharge end of said casing, and a tubular element of smaller size than the interior of said casing, and providing communication 95 between it and said nozzle element, said tubular element terminating short of the inlet end of said casing and having a bore gradually increasing in diameter in the direction of said nozzle element.

DANIEL O. SNOOK.
